UNITED STATES PATENT OFFICE.

VICTOR K. SAMUELSON AND THEODORE J. NELSON, OF CHICAGO, ILLINOIS.

DESIGN FOR A LAMP.

Application filed June 8, 1925. Serial No. 13,708. Term of patent 7 years.

To all whom it may concern:

Be it known that we, VICTOR K. SAMUELSON and THEODORE J. NELSON, citizens of the United States, residing at Chicago, in the county of Cook and State of Illinois, have invented a new, original, and ornamental Design for Lamps, of which the following is a specification, reference being had to the accompanying drawings, forming a part thereof.

Fig. 1 shows our improved design in side elevation and

Fig. 2 shows in plan view the design of

base forming a part of the design shown in Fig. 1, this view being a sectional view through the column taken along the line 2—2 in Fig. 1.

We claim:

The ornamental design for a lamp as shown and described.

In witness whereof, we hereunto subscribe our names this 22nd day of May, A. D. 1925.

VICTOR K. SAMUELSON.
THEODORE J. NELSON.
